UNITED STATES PATENT OFFICE.

BERGET H. BLOCKSM, OF CHICAGO, ILLINOIS, ASSIGNOR TO WILSON & CO., INC., OF CHICAGO, ILLINOIS, A CORPORATION OF NEW YORK.

REFRIGERATOR.

1,353,887.

Specification of Letters Patent. Patented Sept. 28, 1920.

Application filed September 20, 1917. Serial No. 192,270.

To all whom it may concern:

Be it known that I, BERGET H. BLOCKSM, a citizen of the United States, residing at Chicago, in the county of Cook and State 5 of Illinois, have invented certain new and useful Improvements in Refrigerators, of which the following is a specification.

This invention relates to refrigerators and more particularly to insulation therefor, the 10 object of my invention being to provide a more economical and efficient heat insulation whereby the cooling medium of the refrigerator is conserved.

Further objects and advantages of my invention will be apparent as it is better understood by reference to the following specification when read in connection with the accompanying drawing, illustrating the preferred embodiment thereof, in which— 15 Figure 1 is a transverse section through a refrigerator illustrating the application of my invention and

Fig. 2 is a view in perspective of the insulating material.

20 To illustrate my invention I have shown in the drawing an ordinary refrigerator adapted for household use but it is to be understood that my invention has a much wider application and may be employed in 25 large refrigerators such as are used in stores and packing houses and in refrigerator cars. The material may be employed in fact with all constructions where an efficient heat insulating material is desired.

30 Referring to the drawing 5 indicates the outer shell of the refrigerator which in the present embodiment is constructed of two layers of wood and is supported on a suitable base 6. In the corners of the shell I 35 provide spacing members 7 to support an intermediate shell 8 also preferably of wood in spaced relation to the outer shell 5, thus leaving an air space 9. In the corners of the intermediate shell 8 I provide spacers 10 40 to support an inner shell 11 in spaced relation to the intermediate shell 8. The refrigerator may have a metal lining 12 within the inner shell 11. Doors 13 and 14 are mounted in the front of the refrigerator to 45 close suitable openings giving access to the interior thereof. The doors preferably correspond in construction to the remainder 50 of the shell.

In Fig. 2 of the drawing I have illus-

trated a section of a curled hair bat which 55 serves as the insulator for the refrigerator above described. The bat is formed by providing a layer 15 of curled hair and securing a reinforcing fabric 16, such for example as burlap to one face of the layer 60 by forcing portions of the hair through the interstices of the fabric as indicated at 17 in Fig. 2.

Again referring to Fig. 1 it will be seen that a layer 18 of the reinforced curled hair 65 material is disposed between the intermediate and inner shells 8 and 11 and between the corresponding portions of the doors 13 and 14. The chamber of the refrigerator is thus completely surrounded with insulat- 70 ing material.

I have discovered that the reinforced curled hair material described herein constitutes a very superior insulating material for refrigerators of all kinds and that 75 it is extremely efficient in the conservation of the cooling medium. The material is relatively inexpensive and is easily applied in manufacturing refrigerators. Refrigerators which will successfully maintain very low 80 temperatures may be thus constructed at a cost which permits commercial manufacture and sale thereof.

It will be apparent that various changes 85 may be made in the form, construction and arrangement of the parts without departing from the spirit and scope of the invention or sacrificing any of its material advantages, the form hereinbefore described being merely a preferred embodiment 90 thereof.

I claim:

1. In a refrigerator, an outer shell, an intermediate shell, spacer members enveloping each of the corners of said intermediate shell and maintaining said shells in spaced relation to form a dead air chamber therebetween, an inner shell spaced from said intermediate shell, and a layer of curled hair in the space between said inner 100 and said intermediate shells.

2. In a refrigerator, an outer shell, spacer members fitting in each of the interior corners of said outer shell, an intermediate shell within said outer shell and maintained in spaced relation thereto by said spacer members to form a dead air chamber therebetween, spacer members fitting in each of

the interior corners of said intermediate shell, an inner shell within said intermediate shell and maintained in spaced relation thereto by said spacer members, and a layer 5 of reinforced curled hair in the space between said inner and said intermediate shells and surrounding the refrigerator chamber.

3. In a refrigerator, an outer shell, an 10 intermediate shell spaced from said outer shell by spacing members at each of the corners to form a dead air chamber between said shells, an inner shell spaced from

said intermediate shell, a layer of curled hair between said inner and said intermediate shells, and a door giving access to the refrigerator chamber having spaced shells and air chamber corresponding to the shells and air chamber of the refrigerator body, and a layer of curled hair between 20 the inner and the intermediate shells of said door.

BERGET H. BLOCKSOM.
